9 Claims. (Cl. 95—90.5)

The present invention relates to a separating device for holding at a distance from one another the overlapping portions of an article to be treated, and in particular of a photographic or cinematographic film in a developing apparatus.

Tanks for developing films have already been proposed which included an element for separating from one another the spires formed by the film to be developed. Such separating means did not permit of avoiding some drawbacks, in particular scratches and fogs on the films, for instance during winding and unwinding operations.

The object of the present invention is to obviate these drawbacks.

The separating device according to the invention is characterized in that it consists of a strip of an opaque and flexible material, inert with respect to chemical reactions, and in particular to those taking place in developing baths, for instance made of stainless steel, and provided, in close proximity to one of its edges, with at least one row of perforations spaced from one another and in which is engaged a helical spring the pitch of which is equal to the distance between two adjacent perforations.

Advantageously the separating device in question is disposed in a developing apparatus comprising a tank mounted on a support divided into two portions and upon which is adapted a hood also divided into two portions, every portion of the support forming a group with the corresponding portion of the hood, the two groups thus obtained being adapted to be connected together in two relative positions thereof, these two groups being in line with each other in that of the two positions which corresponds to the utilization of the device for instance for developing purposes, whereas these two groups are joined together by the two portions of the support in the other position, which corresponds to transportation of the device.

Concerning said tank, it is advantageously connected to its support by a pivot axis which permits of giving it at will any position between a horizontal position and a vertical position.

Concerning the circulation of the liquids for the treatment of the films, it is ensured, once the tank has been placed in a non horizontal position, by a circuit comprising, on the one hand, a chamber from which the tank is fed with treatment fluid by gravity, and which constitutes an overflow reservoir during washing by water introduced into the same circuit and on the other hand, a pump for the circulation of the liquids.

A preferred embodiment of the present invention will be hereinafter described with reference to the appended drawings given merely by way of example and in which:

FIG. 1 is a plan view of the tank of the apparatus.

FIG. 2 is an axial section on the line II—II of FIG. 1.

FIGS. 3, 4 and 5 show three different constructions of a portion of the separating device;

FIG. 6 is a perspective view of the end of such a separating device;

FIGS. 7 and 8 are views on an enlarged scale, respectively in elevational view and in section on the line VIII—VIII of FIG. 7, of a detail of the tank;

2

FIG. 9 is an elevational view showing the elements of the circuit through which fluids are circulated;

FIG. 10 is an elevational view, with parts torn away, of the whole of the apparatus in position of utilization;

FIGS. 11 and 12 are a front view and a side view, respectively, of the same apparatus in position of transportation.

FIG. 1 shows a tank 1 in the form of a spool on which can be wound the film to be developed and the separating member cooperating therewith. This spool is provided, on its upper plate 2, with two connections 3 for the circulation of treatment fluids, which may be closed by means of hollow cylindrical valves 4 as visible in a more detailed fashion by FIGS. 7 and 8.

Instead of valves 4, we may advantageously use a fixed nozzle provided with extensions consisting of flexible pipes which do not flatten and the shape of which is such that light cannot leak into tank 1, the inner wall of these pipes being such that light is not reflected thereon, this surface being for instance dull and of black colour.

Tank 1 can be brought into vertical position by rotation about two hinges 5, in particular in order to introduce, to extract, or to circulate a treatment fluid.

FIG. 2 shows the film 6 to be developed, this film being spiral wound in tank 1. The successive spires of this film are separated from one another by a separating member 7, also spiral wound. A resilient packing member 8, of toroidal shape, made for instance of sponge rubber, ensures liquidtightness and prevents the inflow of light.

FIGS. 7 and 8 show an inlet 3 on an enlarged scale. Said inlet 3 comprises a hollow sleeve 4 operated by means of a rod 9 and along the axis of which a liquid treatment can flow in, as indicated by the arrows. In the open position, which is that illustrated by the drawing, a lateral opening 4a of sleeve 4 is in register with a corresponding opening of the body, said last mentioned opening being in communication with a rectangular opening provided in the upper side 2 of the tank.

In order to obtain a fluidtight closing of the tank, it suffices to turn rod 9 through about a quarter of a circumference, so as to place the opening 4a of cylindrical sleeve 4 opposite a solid portion of connection 3. Fluidtightness is ensured by packing rings such as 10.

The separating member 7, visible on FIG. 2, consists, according to the invention, of a strip 11 of stainless steel, provided near each of its edges with means for the passage of a liquid.

In the embodiment illustrated by FIG. 3, said means comprise a row of holes 12 at regular interval from one another. In the embodiment illustrated by FIG. 4, the means in question comprise two rows of holes 12, the holes of one row being staggered with respect to those of the other row. In the embodiment illustrated by FIG. 5, the means in question comprise a row of holes 12 and a row of notches 13, said notches being disposed in staggered relationship with respect to said holes. In holes 12, and in the case of FIG. 5 also in notches 13, are engaged the spires of a coil-shaped spring 14, for instance of stainless steel, the pitch of which is equal to the distance between the edges and holes. Each of said springs 14 serves to ensure the desired spacing between the spires of film, while permitting circulation of the treatment fluid between said spires. The whole of strip 11 and spring 14 (engaged in holes 12, in the case of FIGS. 3 and 5, and also in notches 13 in the case of FIG. 4) constitutes an intermediate band which is practically non deformable, strong, opaque to light and does not require particular maintenance. By way of indication, it is noted that spring 14 may be made of stainless steel wire having a diameter of 0.5 mm.

The arrangement of FIG. 3 is advantageous from the point of view of simplicity of manufacture because it requires only one row of holes on every edge of strip 11. The width l of said strip 11 is in this case smaller than the distance d between the side walls of tank 1 by an amount equal to twice the diameter of the wire from which spring 14 is made, that is to say by 1 mm. when the diameter of said wire is 0.5 mm.

However, when it is desired to reduce the possibilities of flow of air or treatment liquids between the edges of the separating member and the inner walls 15 of tank 1, it seems preferable to have recourse to one of the modifications illustrated by FIGS. 4 and 5. In both of these modifications the width l of strip 11 is but very little smaller than the distance d between the inner walls 15 of tank 1.

Also, in order to reduce the possibilities of flow through holes 12, it is preferable to make use of the modifications of FIG. 5 where the total area of the marginal notches 13 is smaller than that of a row of holes 12. Thus a regular flow of the treated liquids on the surfaces of the film is obtained.

Advantageously the length of separating member 7 is greater than that of the film to be treated so that, when film 6 and separating member 7 have been wound in tank 1, separating member 7 overlaps film 6 by at least one complete turn and thus ensures an efficient protection against light so as to avoid fogging of the end of the film when the cover of the tank is opened as it will be hereinafter explained.

In order to prevent separating member 7 from unwinding spontaneously, it is provided at one of its ends with an element such as shown by FIG. 6. This element consists of a plate spring 16 some millimeters wide, fixed on said separating member 7, for instance by rivetting, perpendicularly to its axis. The two ends of spring plate 16 are folded at substantially right angle and are adapted to bear against the inner faces of the side walls of tank 1.

Furthermore the end of the separating member may be engaged in a resiliently mounted part fixed to the axis of a magazine spool from which said separating member is extracted.

In another blocking system, separating strip 7 is provided with a magnetic element, for instance a magnet or a ferrite piece fixed to one of its ends, this element being adapted to be fixed on a steel or ferrite piece, itself mounted on the preceding spire of the separating member.

The apparatus will now be described with more specific reference from FIGS. 9 to 12 inclusive.

The film to be developed being wound on a spool rotatable on a spindle 41 whereas separating member 7 is wound on spool 42, the end of said film and the end of separating member 7 are both secured to the core 1a of spool-shaped tank 1. The opaque hood 30a, 30b is then fixed in position on support 31a, 31b and crank 37, the extensions 37a and 37b of which bear, inside the apparatus, on parts 3, is operated so as to wind both the film and separating strip 7 around the core 1a of spool 1.

Owing to its length, which is greater than that of the film, separating strip 11 surrounds said film over at least one supplementary turn. The end of said separating strip is fixed in position by means of the fixation device above described so that spontaneous unwinding is made impossible. Experience teaches that the protection thus obtained with an opaque separating strip according to the invention is sufficient to permit of removing hood 30a, 30b and of setting resilient packing member 8 in position, thus ensuring liquidtight and lighttight protection of the film.

Tank 1 is then pivoted into the non horizontal position where the film is treated by successive baths.

FIG. 9 diagrammatically shows, by way of example, a circuit for circulation of the liquid necessary for the treatment of the film. Connections 3 are so disposed that

the liquid circulation pipes can be fitted thereon quickly without risk of fogging the film.

Connections 3 are connected together by a pipe 17 in which is interposed a pump 18, suitably driven, either electrically or mechanically. A vessel 20 is in communication with the upper connection 3 of tank 1, said vessel 20 serving to the introduction of the baths into tank 1. During the operation, 20 may also act as an expansion vessel and serve to the evacuation of the air bubbles which may form in tank 1. Vessel 20 is connected through a pipe 21 with a conduit 22 serving to the evacuation of liquids. Washing water may be fed through a conduit 23. Valves 24 and 25 make it possible to separate the circuit from conduits 22 and 23.

This arrangement is used in the following manner: Valves 24 and 25 being closed, the treatment liquid is introduced into vessel 20 and pump 18 is operated. If it is supposed that pump 18 forces liquid through the portion of pipe 17 located above said pump, this liquid is then introduced through the upper connection 3 into tank 1, passes through said tank, flows out therefrom through the lower connection 3 and returns to the pump through the lower branch of conduit 17. A circulation of liquid is thus ensured in tank 1. Once this liquid has acted for a sufficient time on the film present in tank 1, the pump is stopped and said tank 1 is emptied by opening valve 24. Of course the liquid flowing out through pipe 22 may be collected so as to be reutilized. The same operation is repeated for each of the different liquids to be used. In order to wash the film, it suffices to close valve 24 and to open valve 25, pump 18 being in operation. The overflow of water first fills vessel 20 and then flows out through pipe 21.

After this washing operation, the film is dried by blowing air, possibly slightly heated, through tank 1, by means of a fan connected with the circuit above described.

After these developing, washing and drying operations, the film is wound upon the spool (not shown) fitted on spindle 41 whereas separating strip 7 is wound upon the magazine spool 32.

For this purpose, the end of the film and the end of the separating strip are secured to their respective spools and spool 32 is rotated by means of the crank. Tank 1 is thus caused to rotate about its spindle 39. Tank 1 drives a roller (not shown) free to rotate about its axis and in contact with a circumferential part of said tank. This roller in turn drives said spool for the winding of the developed film, while being able to slip slightly so as to compensate for the difference between the circumferential speeds of winding.

The hole 37c in which the external arm of the crank is engaged may be connected to an element 38 carried by the portion 30b of the hood by means of a bar (or by means of the horizontal arm of the crank) which may then serve to transportation of the apparatus in the position of utilization.

FIGS. 10, 11 and 12 show a film developing apparatus made according to a preferred embodiment of the invention.

The whole of the devices and parts which constitutes said apparatus is mounted on a support divided into two portions 31a and 31b adapted to be fitted together. Each portion of the support and the corresponding portion of the hood form a group. Hood portions 30a and 30b may be placed in line with each other in the position of utilization illustrated by FIG. 10, where, of course, portions 31a and 31b are also in line with each other. The hood portions 30a, 30b are fixed on the support by screws 35.

Tank 1 is mounted in the portion 31a of the support in such manner as to rotate about its vertical axis 39 and said tank can be pivoted about a horizontal axis due to the provision of hinges 5 so that said tank may occupy, at will, any position between a horizontal and a vertical one. The portion 31a of the support also carries a lamp 40.

Portion 31b of the transport carries the spool 32 on

which the separating means 7 can be mounted and this spool 32 is rotatable about spindle 42. Portion 31b also carries the pin 41 intended to support the spool on which the film to be developed is initially wound.

In the position illustrated by FIGS. 11 and 12, for transportation of the apparatus, portions 31a and 31b of the support are assembled together and fixed to each other on the one hand by means of a handle 36 secured by screws 35 and on the other hand by means of bars 34 (having bent ends) which are fixed to the portions 31a and 31b of the support.

The hood 30a, 30b is set in position only for winding the film in the developing tank.

In the apparatus which has been described, the film is helically wound to form spires between which the separating means 7 are interposed.

But of course the film might be accordion plaited and in this case the separating member is also accordion plaited.

The device according to the present invention is not limited to film developing apparatus. It may be used advantageously in any chemical or electro-chemical treatment apparatus and also in any washing, drying, or other apparatus where it is necessary to keep at some distance from each other respective surfaces of an object to be treated so as to permit the flow of the treatment fluid between these surfaces.

In the case where the invention is applied to an apparatus for developing a photographic or cinematographic film, this invention has the further advantage not only of protecting the sensitized surface of the film against light but also of avoiding any possibility of scratching of the film surface by the separating means, the springs 14 which extend along the edges of separating strip 11 being in contact exclusively with the marginal portions of the sensitized surface which bear no picture.

In a general manner, while the above description discloses what are deemed to be practical and efficient embodiments of the invention, said invention is not limited thereto as there might be changes made in the arrangement, disposition and form of the parts without departing from the principle of the invention as comprehended within the scope of the appended claims.

What we claim is:

1. An apparatus for the treatment of a band by a liquid, said band being packed so that respective portions thereof are located opposite one another, which apparatus comprises, in combination, a tank having two walls parallel to each other and between which said band is disposed edgewise so as to fit in the space between said walls, a strip of flexible material packed in a manner similar to that in which said band is packed so that every portion thereof is located between corresponding portions of said band, said strip being provided, near one of its edges, with at least one row of holes located at equal intervals from one another, a helical spring of a pitch equal to the distance between two adjacent holes of said row passing through said holes so as to keep said strip at a uniform distance from said band, and means for circulating a fluid through said tank.

2. An apparatus for developing a spiral wound film which comprises, in combination, an annular tank having two parallel flat walls at a distance from each other a little greater than the width of said film so that the film can be wound in said tank, a strip of flexible, opaque material, inert to film developing chemicals, the width of said strip being smaller than the distance between said walls, so that said strip can be wound helically in said tank in interspacing relation with a film helically wound therein, said strip being provided, near each of its edges, with at least one row of holes located at equal intervals from one another, a helical spring of a pitch equal to the

distance between two adjacent holes of each of said rows passing through said holes so as to keep said strip at a uniform distance from said film, and means for circulating a liquid through said tank.

5 3. An apparatus according to claim 2 wherein said strip is made of stainless steel.

4. An apparatus according to claim 2 wherein said strip is provided near each of its edges with a single row of holes.

10 5. An apparatus according to claim 2 wherein said strip is provided near each of its edges with two rows of holes, the holes of said two rows being staggered with respect to those of the other one.

15 6. An apparatus according to claim 2 wherein each of the edges of said strip is provided with a series of notches and near said edge with a series of holes, said notches being at the same distance from one another as said holes and being staggered with respect thereto.

7. An apparatus according to claim 2 further comprising means carried by said strip at one end thereof for preventing unwinding of said strip in position in said tank.

20 8. An apparatus for developing a spiral wound film which comprises, in combination, two support portions substantially in the form of plates, two hood portions adapted to fit on said support portions, every support portion forming a group with one of said hood portions, respectively, an annular tank rotatably mounted on one of said support portions, about an axis, said annular tank

25 having two parallel flat walls at a distance from each other a little greater than the width of the film so that said film can be wound helically in said tank, a spool journaled on the other of said support portions about an axis for receiving a strip of flexible opaque material, inert to film

30 developing chemicals and of a width smaller than the distance between said annular tank walls, and means for assembling said two groups together in two different ways, to wit according to a first way with said plates in line with each other and the axis of said annular tank parallel

35 to the axis of said spool, for film developing, and according to a second way with said plates facing each other, parallelly to each other, for transportation of the apparatus.

9. An apparatus for developing a spiral wound film which comprises, in combination, a horizontal support, an annular tank having two parallel flat walls at a distance from each other a little greater than the width of said film so that the film can be wound in said tank, said tank being pivotally mounted on said support about an axis

40 parallel to said flat walls so that it can be given any desired position from a horizontal one to a vertical one, a strip of flexible opaque material, inert to film developing chemicals, the width of said strip being smaller than the distance between said walls, so that said strip can be

45 wound helically in said tank in interspacing relation with a film helically wound therein, said strip being provided, near each of its edges, with at least one row of holes located at equal intervals from one another, a helical spring of a pitch equal to the distance between two adjacent

50 holes of each of said rows, passing through said holes so as to keep said strip at a uniform distance from said film, and means for circulating a liquid through said tank.
